(57) **CLAIM**

The ornamental design for an air ratchet tool handle, as shown and described.

DESCRIPTION

FIG. 1 is a left side view of an air ratchet tool handle showing our new design;

FIG. 2 is a right side view of FIG. 1;

FIG. 3 is a top view of FIG. 1;

FIG. 4 is a bottom view of FIG. 1;

FIG. 5 is a front view of FIG. 1; and,

FIG. 6 is a rear view of FIG. 1.

The structural features depicted by means of broken lines in the drawing figures have been shown for illustrative purposes only and form no part of the claimed design.
